UNITED STATES PATENT OFFICE.

SAMUEL E. GREENWAY, OF DELORAIN, CANADA.

DESIGN FOR A PAPER-WEIGHT.

SPECIFICATION forming part of Design No. 31,071, dated June 27, 1899.

Application filed May 3, 1898. Serial No. 679,635. Term of patent 7 years.

To all whom it may concern:

Be it known that I, SAMUEL E. GREENWAY, a subject of Her Majesty the Queen of Great Britain, residing at Deloraine, in the Province of Manitoba, Dominion of Canada, have invented and produced a new and original Design for a Paper-Weight, of which the following is a specification.

This invention relates to a new and useful design for a paper-weight.

The leading feature of my design consists in the circular shape of the body, having the representation of a horseshoe impressed or designed therein, with openings at various intervals.

Referring to the drawings, Figure 1 is a perspective view of my design, and Fig. 2 is a sectional view thereof.

My design comprises a circular block A, in

the front face of which is produced the representation of a horseshoe, the rear face of said block being chambered or recessed, as shown at C in Fig. 2. An elliptical opening D is designed in the upper portion of the horseshoe, and similar-shaped openings are arranged adjacent to each end of the horseshoe. A circular opening is arranged adjacent to the ends and about equally distant from each end.

Having thus fully described my invention, what I claim as new, and desire to secure by Letters Patent, is—

The design for a paper-weight, substantially as shown and described.

SAMUEL E. GREENWAY.
